UNITED STATES PATENT OFFICE.

ELMER A. TERPENING, OF GENESEO, ILLINOIS.

ELECTRORESPONSIVE DEVICE.

No. 810,311.

Specification of Letters Patent.

Patented Jan. 16, 1906.

Application filed December 17, 1904. Serial No. 237,322.

To all whom it may concern:

Be it known that I, ELMER A. TERPENING, of Geneseo, in the county of Henry and State of Illinois, have invented certain new and 5 useful Improvements in Electroresponsive Devices; and I hereby declare that the following is a full, clear, and exact description thereof, reference being had to the accompanying drawings, which form part of this 10 specification.

My invention relates to improvements in signalling apparatus, and has for one of its primary objects to provide an electrically-responsive apparatus which will be highly 15 sensitive and relatively powerful in its mechanical actions occasioned by its electric sensibility.

In many types of electric installation it is 20 highly desirable to have an electroresponsive device of high sensibility wherein the passage of very weak electric currents will produce mechanical movements of some part of the responsive apparatus of relatively great power sufficient to perform certain mechanical work, such as the operation of an auxiliary electric-circuit closer, the release of a 25 signal mechanism, or the like. For example, in telephony it is highly desirable that central stations should be equipped with electroresponsive apparatus of such electric sensibility and mechanical efficiency for inclusion 30 in the calling-circuit and association with the signaling apparatus designed to attract the attention of the operator when a call is received. Further, it is advantageous in telephone selective call systems to provide such a sensitive and efficient electroresponsive device in association with step-by-step 35 selective mechanism to actuate such selective mechanism, and in telegraphy it is highly 40 advantageous to employ an electroresponsive device with the characteristics of great sensibility and relatively high mechanical efficiency described as a relay, as thereby the 45 distance of transmission by a single line may be increased, and in many instances iron wires may be employed where copper wires are now necessitated by the relatively low 50 sensibility and efficiency of relays of the type now in use in which the current required to operate the mechanical parts must be relatively strong. Numerous other advantageous 55 applications of electroresponsive devices having the characteristics of the device of my present invention will occur to those skilled in the art, and without intending to

limit my invention to such applications, but for purposes of a full disclosure, I have herein illustrated the application of my invention to the three uses which I have above specified. 60

In the drawings, Figure 1 is a front view or elevation of an embodiment of my invention well adapted for employment as a relay in conjunction with telephone appliances. Fig. 2 is a plan view thereof. Fig. 3 is a section 65 on line 3 3 of Fig. 1. Fig. 4 is a diagrammatic plan of a device adapted for actuating step-by-step selective apparatus for telephone purposes, and Fig. 5 is a diagrammatic illustration of an application of my invention 70 to a telegraph-relay.

Throughout the drawings like numerals of reference refer always to like parts.

Referring now to the specific construction of current-responsive device shown in Figs. 1, 2, and 3, 10 indicates a suitable base upon which is mounted in a suitable supporting-frame structure, generally indicated as 11, two sets of magnets 12 12 and 13 13, preferably all permanent horseshoe-magnets. The 80 magnets of the two sets have their arms spread to different extents and are so disposed and supported in frame 11 that the poles of the magnets 13 13 extend between the poles of the magnets 12 12 and are suitably separated therefrom. The magnets are so arranged that the magnets 12 12 of the outer set have their like poles together, and the inner magnets 13 13 have their like poles together; but the two sets of magnets are arranged 85 with their opposite poles in confronting relation—that is to say, the negative poles of the outer magnets 12 12 confront the positive poles of the inner magnets 13 13, and vice versa, so that a very strong magnetic field is 90 formed in the space intervening on each side between the inner and outer sets of poles. Any suitable number of magnets 12 12 and 13 13 may be provided, the magnets of like size being arranged in vertical alinement and 95 preferably having their ends connected by continuous pole-pieces 12' 12' and 13' 13', respectively. The proximate surfaces of the pole-pieces 12' and 13' are spaced apart sufficiently to accommodate the side pieces of an 100 oscillating coil-frame 14, preferably made of wood or other insulating material, and preferably comprises solid end portions 14' 14', connected by side strips 14² 14², which extend through the spaces between the pole-pieces 12' 13' of the outer and inner magnet 105 sets, and further connected by a central 110

2

strip 14³, extending between the arms of the inner magnet 13 13. Upon this coil-frame 14 is wound a coil 15 of suitable fine wire for a purpose to be described. The arrangement of the coil-frame 14 is such that it may oscillate through a small angle between the magnets, and to this end it is maintained in vertical position in suitable insulating bearings 16 16', but is preferably freely suspended therein by a wire 17 (preferably of German silver or like material) at its upper end, supported by but insulated from any suitable bracket 18 and at its lower end electrically connected to the wire of the coil 15. 15 With the wire 17 is connected a suitable wire 19, which leads to a binding-post 20 on any suitable portion of the machine. The extremity of the coil 15 is connected with the wire 21, passing through the insulated bearing 16' and connected with a wire 22, leading to a binding-post 23, preferably arranged in pair with the binding-post 20. The binding-posts 20 and 23, it will be understood, are designed to receive the wire leading from the exterior circuit with which the electroresponsive device is to be connected to receive its actuating-current.

I have found that the construction above described provides an electroresponsive member of very great sensitiveness and of high mechanical efficiency. The arrangement of the magnets relative to the coil is such that one magnet presents its poles to the exterior of the coil, and the other magnet presents its poles to the interior of the coil, affording thereby a very strong magnetic field in which the coil works, renders the coil extremely sensitive to current, and a very weak current passing through the coil will cause its strong deflection in one direction or the other, according to the direction in which the current passes therethrough. Further, I have found that an apparatus embodying such an arrangement of coils and magnets is not susceptible to many of the troubles, such as hysteresis, which affect polarized relays and such electroresponsive devices as have been heretofore commonly employed. The efficiency of the responsive device or the torsional pull of the coil, even under very weak current, is so strong that its action may be utilized for many purposes.

In the embodiment of my invention shown in Figs. 1, 2, and 3 I have illustrated a construction wherein the apparatus acts as a relay, a secondary circuit being controlled through a circuit make-and-break device by the movement of the oscillating coil. Further, in such embodiment I have shown a means for rendering the apparatus operationally sensitive to current of one nature and direction only, and the specific means whereby I accomplish these results I will now describe. 24 indicates a stationary contact-screw carried by a conducting-strip 25,

mounted in an insulating-block 26 above a recess formed in the face of said block. 27 indicates the movable contact-point playing vertically in the recess in the block and carried by a rocking shaft 28, transversely 70 mounted in insulated bearings 29 29, supported in any suitable manner. From the shaft 28 depends a vertical rod 30, the lower end of which is operatively associated with a retarding device to be hereinafter described. 75 Intermediate its end the rod 30 is spanned by the slotted end of an arm 31, the opposite end of which is secured to the central piece 14³ of the oscillating coil 15. The movable contact part 27 is preferably adjusted as to balance by a weight 32, mounted for adjustment upon a rod 33, extending at right angles to the axis of the shaft 28. I prefer that the lower end of the rod 33 be extended forward, as at 33', to contact with the stationary contact member and its insulating-block 80 85 90 95 100 105 110 115 120 125 130 26 to form a stop to limit the throw of the movable contact member in either direction and take the strain therefrom, as will be well understood by those skilled in the art. The retarding device heretofore adverted to is preferably a dash-pot and in the construction shown comprises a liquid-receptacle 34, suitably supported, and containing a casing 35, open at one side and supported as upon a rod 36, suitably secured to the framework 11. 37 indicates the dash-pot plunger secured to the rod 30. Preferably the plunger 37 is centrally perforated. The perforation is covered on one side by a valve 38, so that the member 37 is relatively quickly movable in one direction and relatively slow of movement in the other direction. Preferably also for the present purpose the direction in which the plunger 37 is freely movable is that which corresponds with the movement of the movable contact member 37 away from its stationary contact-point 24. Now it will be apparent that if current is passed through the coil 15 in one direction it tends to throw the arm 31 in such direction that through the stem 30 and rock-shaft 28 it moves the movable contact member 27 into contact-making position relative to its stationary member 24. In causing such movement of the contact parts it will be noticed the coil has to overcome the maximum resistance of the dash-pot, the valve 38 closing the aperture or plunger 37 when said plunger is moved to the left, Fig. 3. If current be passed through the coil in the opposite direction, it tends to move the contact part 27 to its utmost limit away from the stationary contact member 24 or until the stop-rod 33' contacts with the frame; but in so doing the coil has to overcome the minimum resistance of the dash-pot, the valve 38 whereof opens to movement in this said direction. The resistance of a dash-pot in a device of this character is sufficient to render the action of the

contact devices sluggish enough to prevent an alternating current of any ordinary frequency from ever causing contact to be made between the contact members, and it will be apparent that the valve arrangement of the dash-pot making its resistance to movement in opposite directions unequal causes the plunger to work in the direction tending to move the contact members to their farthest separated position when alternating current passes through the coil, and so reduces the liability of accidental closing of the contact parts. The contact parts 27 and 24 are shown as connected by wires 39 and 40 with binding-posts 41 and 42, which, it will be understood, form part of the circuit to be controlled by the relay—such, for instance, as an annunciator or drop-circuit of a telephone-switchboard. Thus in Figs. 4 and 5 I have illustrated two of the many possible applications of my invention wherein the coil 15 is arranged in each case in a strong magnetic field between the sets of magnets 12 12 and 13 13, as heretofore described, but wherein the retarding device is omitted.

In Fig. 4 the rod 31, connected with the coil-frame 14, as before described, carries at its extremity a pawl 50, arranged to act upon a ratchet-wheel 51. It will be apparent that intermittent current of proper direction, alternately advancing and retracting the pawl 51, advances the ratchet. Such a movement is of wide applicability and may be used in step-by-step selective telephone signal apparatus and elsewhere, as will be understood by those skilled in the art.

In Fig. 5 I have shown diagrammatically the embodiment of my invention in a telegraph-relay, the arm 31 actuating a movable contact part 52 of a normally open circuit 53, including a source of current-supply 54 and a telegraph-sounder 55.

While I have herein particularly described certain advantageous embodiments of my invention, it is for full disclosure that details are shown and described and without intent to limit myself thereto further than as specified in the claims.

Having thus described my invention, what I claim, and desire to secure by Letters Patent of the United States, is—

1. In a current-responsive device adapted for actuation by feeble currents, two horse-shoe-magnets arranged with opposite poles in proximity to leave therebetween two spaces constituting two strong magnetic fields, a coil having its two sides in said spaces and adapted for connection in a line, means for suspending said coil for oscillation, means for retarding the oscillation of said coil, and working parts associated with the coil to derive their working power from the oscillation of said coil.

2. In a current-responsive device two magnets arranged with opposite poles in separated arrangement in such proximity that

they jointly create two magnetic fields, and a coil supported for oscillation with its windings passing between said poles of the magnets, one side of such winding lying in each magnetic field, and said coil being arranged for connection in a circuit.

3. In a current-responsive device, two magnets arranged with opposite poles in separated arrangement in such proximity that they jointly create two magnetic fields, a coil adapted for connection in an electric circuit having its windings passing between the said poles of the magnets, one side lying in each magnetic field, said coil being supported for deflection, and working parts associated with the coil to derive their working power from its oscillation.

4. In a current-responsive device, permanent magnets arranged with the poles of one between the poles of the other, a coil suspended for oscillation with its windings passing down between the proximate poles of the magnets on one side and up between the opposite proximate poles of the magnets on the other side, and working devices connected with the coil for actuation by its oscillation.

5. In a current-responsive device, two magnets arranged with opposite poles in separated arrangement in such proximity that they jointly create two magnetic fields, a coil adapted for connection in an electric circuit having its windings passing between said poles of the magnets, one side of such coil lying in each magnetic field, and said coil being supported for deflection, working parts associated with the coil to derive their working power from its oscillation, and means for retarding the oscillation of the coil, arranged to effect a greater retardation of the movement of the coil in one direction than of its movement in the other direction.

6. In a current-responsive device two magnets arranged with opposite poles in separated arrangement in such proximity that they jointly create two magnetic fields, a coil adapted for connection in an electric circuit having its windings passing between said poles of the magnets, one side of the coil lying in each magnetic field, and said coil being supported for deflection, contact parts comprising a movable member adapted to be operatively moved by deflection of the coil in one direction and a dash-pot operatively associated with the coil arranged to effect a greater retardation of the movement of the coil in the direction to operate the contact than to its movement in the opposite direction.

7. In a current-responsive device, a pair of permanent magnets, arranged with their opposite poles in separated but proximate relation to create two strong magnetic fields, a single coil supported for oscillation with its sides respectively in said fields, said coil being adapted for connection in an electric circuit, and signaling devices operatively con-

5
nected with said coil for actuation by move-
ment thereof in one direction.

8. A relay comprising two permanent horse-
shoe-magnets arranged with the poles of one
in such separated, proximate relation to the
poles of the other as to establish therebetween
two strong joint magnetic fields, a coil
mounted for deflection with its windings
passing between two proximate poles of the
magnets one side and between the remaining
poles on the other and adapted for connection
in a main circuit, contact devices arranged for
connection in another circuit, and operative
connections between the movable element of
said contact devices and the oscillating coil
whereby said contact devices are actuated by
movement of the coil.

9. A relay comprising a permanent magnet
arranged to constitute a magnetic field, a coil
supported for oscillation in the field, means
for retarding the oscillation of said coil, con-
tact devices including a movable part and
operative connection between the movable
part of the contact device and the oscillating
coil.

10. In combination, a pair of horseshoe-
magnets with their opposing poles in proxim-
ity and parallelism in a common plane, a sin-

gle coil adapted for connection in a circuit
suspended with its sides passing between the 30
opposite coacting poles of the two magnets, a
contact device, a dash-pot connected with
the contact device, and an operative connec-
tion between the coil and said connected
parts whereby movement of the coil actuates 35
the contact device and is retarded by the
dash-pot.

11. In combination, a pair of magnets with
their opposing poles arranged in proximity to
jointly create two strong magnetic fields, a 40
coil adapted for connection in a circuit sup-
ported for deflection with its sides respec-
tively in said two fields, a dash-pot having its
movable element suspended, a connection
between said coil and the suspension of the 45
dash-pot, and working parts associated with
the coil to derive their working power from
oscillation of the coil.

In testimony that I claim the foregoing as
my own I affix my signature in presence of 50
two witnesses.

ELMER A. TERPENING.

In presence of—
PHINEAS MORROW,
F. H. McARTHUR.
